J. V. CIZEK.
PORTABLE ELEVATOR.
APPLICATION FILED MAR. 11, 1912

Patented Oct. 20, 1914.

UNITED STATES PATENT OFFICE.

JOHN V. CIZEK, OF CLUTIER, IOWA.

PORTABLE ELEVATOR.

1,114,112.

Specification of Letters Patent. Patented Oct. 20, 1914.

Application filed March 11, 1912. Serial No. 683,167.

To all whom it may concern:

Be it known that I, JOHN V. CIZEK, a citizen of the United States, residing at Clutier, in the county of Tama and State of Iowa, have invented certain new and useful Improvements in Portable Elevators, of which the following is a specification.

This invention relates to farm elevators used in conveying grain, cribbing corn, and the like, and embraces certain improvements in the construction of such elevators, the object of which is to render them more easily portable, and to increase their general efficiency as will be more fully set out hereafter.

The invention is clearly disclosed in the description and claim following, reference being had to the accompanying drawings, in which—

Figure 1 is a general view in perspective of an elevator embodying my improvements. Fig. 2 is a fragmentary longitudinal section of the main conveyer, showing a removable grid set in the bottom of the upper deck and a discharge spout below it for shelled corn passing through the grid. Fig. 3 is a view of the grid in perspective.

The elevator proper is mounted on a supporting frame provided with suitable carrying wheels A, described in a divisional co-pending application No. 761,102, filed April 14, 1913.

B B are two longitudinal bars connecting the front cross-bar C and the rear axle-bars D. The connection at the rear is direct, as will be seen, being fastened between the axle-bars. At the front end, however, the reach-bars B B connect with yokes E, which serve as guides for the main driving shaft F. These yokes are secured rigidly to the front cross-bar, and thus form parts of the rigid main frame on which the elevator is mounted. To the front cross-bar is pivotally attached the front axle G, which is provided with knuckles H to receive the front carrying wheels.

The conveyer is of the endless apron type, and comprises an adjustable receiving portion at the forward end of the machine, and a discharging body extending over the running-gear and to a considerable distance to the rear thereof, this extension being indicated by a break in the rear section, as shown in Fig. 1. The elevator is used largely in cribbing corn, and in this operation there is more or less shelling of the corn from the cob. It is not desirable to

crib this shelled corn, as it is apt to gather in more or less compact masses in the crib and there heat and mold. Accordingly provision is made for riddling out the shelled corn as it passes up the conveyer. The construction is clearly shown in Figs. 2 and 3.

The elevator K is provided with an upper and lower deck, K¹ and K², respectively, the conveyer K³ running over the upper deck in the usual way. In the upper deck is provided a considerable opening and in this is fitted a removable grid K⁴, the slots in which permit the shelled corn to pass through, but are narrow enough to carry the ears of corn. Across a gap in the lower deck is fixed an iron-lined spout K⁵ to carry the shelled corn out of the conveyer.

It will be seen that the main elevator is hinged at K⁶, so that the rear section may be folded back over the mid-section for convenience in transportation.

The elevator is suspended by means of a stirrup K⁷, provided with a suitable sheave K⁸, from a derrick L pivoted at L¹ to the rear axle. At one side of the derrick is a winch L², preferably provided with a worm-gear and hand-lever, as shown. Around the drum of the winch runs a cable L³, passing thence over a sheave L⁴, thence under the stirrup sheave K⁸, and up to a connection with the opposite side of the derrick near the top. The elevator may thus be easily hoisted to any desired elevation. When completely depressed it rests on the rear axle, and the derrick may then be folded forward in the same manner as the rear section of the elevator.

At the front end the mid-section of the elevator is provided with suitable bearings M, both to support the front or hopper section of the elevator, and also for the driving shaft therefor. On one of these bearings is pivotally mounted a bearing bracket N adapted to take a horizontal shaft for a bevel-gear O, and a short shaft perpendicular thereto, for a pinion O¹. Slidably connected with this bracket is another bracket N¹ similarly adapted to take a short shaft for a pinion O², and the main driving shaft F already referred to. The short shafts for the pinions are made to telescope together, one of them being preferably square, as shown. The brackets may thus be moved in or out with respect to each other for any desired adjustment. A hub of the lower bracket projects into the slot in

the yoke E, and by means of cables P passing over suitable sheaves P¹ and attached to a winch P², the whole forward end of the elevator may be raised or depressed at will.

5 The forward section of the elevator, Q is provided with hinged side-boards Q¹, which may be tilted downwardly, as is shown in the case of the nearer one, for convenience in shoveling in material. This section tilts in 10 a circle concentric with the shaft which drives its conveyer. Suspension leverage is provided in standing bars Q² and Q³ connected by tie-rods Q⁴. To the inner pair is attached a pair of cables R, connecting at 15 their other ends with a winch S. The elevator section may thus be set with its forward end near the ground, or at any desired elevation above it, and when not in use it may be folded back over the mid-section for convenience in moving from place to place.

Having thus described my invention, what is claimed is:

In an elevator, the combination of a sup-

porting frame, the frame having slotted yokes near the front end for the driving 25 shaft to pass through, a discharging conveyer mounted over said frame pivotally at its forward end, bearings for the driving shaft attached thereto, a shaft mounted therein and passing through the yokes, a 30 bevel gear thereon, a receiving conveyer pivotally attached to the discharging conveyer at its forward end, a driving shaft therefor provided with a bevel gear, a telescoping cross-shaft with pinions thereon meshing 35 with said bevel-gears, respectively, and brackets for said shafts attached slidably together, whereby the distance between the said driving shafts may be varied, as specified.

In testimony whereof I affix my signature in presence of two witnesses.

JOHN V. CIZEK.
